UNITED STATES PATENT OFFICE.

WILLIAM H. HARTMAN, OF LOS ANGELES, CALIFORNIA, ASSIGNOR TO RANDALL CONTROL AND HYDROMETRIC CORPORATION, OF LOS ANGELES, CALIFORNIA, A CORPORATION OF CALIFORNIA.

ELEVATOR-DOOR-LOCK-CONTROL MECHANISM.

Application filed November 23, 1920. Serial No. 425,969.

To all whom it may concern:

Be it known that I, WILLIAM H. HARTMAN, a citizen of the United States, and a resident of Los Angeles, county of Los Angeles, and State of California, have invented a certain new and useful Elevator-Door-Lock-Control Mechanism, of which the following is a specification.

The invention relates to elevator shaft door locks, and particularly to means for operating the lock.

An object of the invention is to provide a mechanically operated elevator shaft door lock.

Another object of the invention is to provide a door lock which is held open during the time that the door is open and which operates to lock the door as it reaches closed position.

A further object of the invention is to provide means for preventing the operation of the elevator motor during the time that a door is unlocked.

The invention possesses other advantageous features, some of which, with the foregoing, will be set forth at length in the following description, where I shall outline in full that form of the invention which I have selected for illustration in the drawings accompanying and forming part of the present specification. In said drawings I have shown one form of the apparatus of my invention, but it is to be understood that I do not limit myself to such form, since the invention, as expressed in the claims, may be embodied in a plurality of forms.

Referring to said drawings:

Figure 1 is an elevation of a portion of an elevator car, partly in section, with the apparatus of my invention installed thereon.

Figure 2 is an elevation of the door lock with the front plate removed, showing the bolt on the door in locked engagement.

Figure 3 is an elevation of a portion of the mechanism on the car in engagement with the lock, which has been moved to open position.

Figure 4 is a view, partly sectional, from the bottom of the car, of the detent for the controlling handle.

The invention is applicable to elevators, operating in shafts having a plurality of sliding doors, one arranged at each floor. A lock, secured to the structure of the ele-

vator shaft, is arranged at each door, and each door is provided with a bolt 2, which engages the lock, to hold the door in locked position. The lock is enclosed in a case 3, into which the bolt extends, and is provided with a latch lever 4, which engages a notch in the bolt. The lever 4 is usually of the bell crank variety, one arm 5 of which projects through a slot in the top of the casing 3. Pivoted to the case and engaging the end of arm 5 is a lever 6, having a counterweight 7 placed to one side of the pivot, so that the lever 6 is normally inclined in such position to hold the latch 4 elevated and the bolt locked. The lever 6 is provided on its free end with a pin or projection 8, which projects into the elevator shaft and by engagement with which the lever 6 is rocked.

In the arrangement shown in Fig. 2, movement of the pin 8 to the right, depresses the latch 4, so that the bolt 2 may be withdrawn. Means are provided, which move into position as the bolt is withdrawn, for locking the latch in the depressed position and holding it in such position until the bolt is again inserted into the casing. Pivoted within the casing is a weighted lever 9, having a notch 13 therein, which engages a pin 14 on the depressed latch when the bolt is withdrawn. A second lever 15 is provided with a notch 16, which engages a pin 17 on the arm 5 as the bolt is withdrawn. One of these levers is sufficient to lock the latch in open position, but I prefer to employ both, so that the proper operation of the lock will be assured in the event of the failure of one of the levers to operate. When the bolt is reinserted into the casing, these levers are moved out of contact with the latch, which is then moved into engagement with the bolt 95 by the overbalancing weight of the mass 7.

Means are carried by the elevator car which move into engagement with the pin 8, as the car reaches a position at a floor and this means is then actuated to move the lever 6 to release the bolt. Mounted on the elevated car, by the parallel levers 18, is a substantially vertically disposed actuating member 19, having a substantially vertical slot 21 therein, flaring outwardly at the top and bottom, to insure the positioning of the pin in the slot. The levers 18 are of such form that vertical movement of the outer

ends of the levers produces a transverse movement of the member 19, thus causing a transverse movement of the pin 8, which unlatches the lock. Connected to the outer 5 ends of the levers 18, is a rod 22, which extends to a position below the floor of the car, where it is connected to the lever 23, pivoted to the car floor. Connected to the lever 23 is a spring raised pedal 24, which, 10 when depressed, moves the member 19 laterally.

When the car is stopped at a floor, the operator depresses the pedal 24, thus unlocking the door, which may then be opened 15 by hand or by any power operated means. The initial opening movement of the door locks the latch open and the operator may then remove his foot from the pedal. When the door is subsequently moved to full closed 20 position, the latch locking levers are released and the latch and actuating member 19 return to normal position.

Means are provided for preventing the operation of the car during the time that the shaft door is unlocked, or in other 25 words, during the time that the rod 22 is in depressed position. The movement of the car is controlled by the lever 25, to which is secured a gear 26 engaging the vertically 30 movable rack 27. Secured to and movable with the rack is a rod 28, having a neck 29 of less diameter than the rod, which is preferably disposed adjacent the under side 35 of the car floor. Slidably mounted on the under side of the car floor is a slide 31, having a bifurcated end provided with a tapering slot, as shown in Fig. 4. When the slide 31 is moved to the left, the rod 28 is free to move, but when the slide 31 is moved 40 to the right, it forms a barrier for the shoulders at either side of the neck 29, thereby precluding movement of the rod 28. It is understood that when the lever 25 is moved 45 to neutral position, that the neck is disposed in the plane of the slide and when in this position may be engaged by the slide 31, which then operates as a barrier. The slide 31 is connected to the rod 22 by the bell 50 crank lever 32 and the adjustable link 33 and the link 34, so that depression of the rod 22 locks the control lever 25 in neutral position. The control lever is relieved of the weight of the rack and rod by the counterbalancing lever 36.

55 I claim:

1. The combination with an elevator shaft door, of a bolt on said door, a lock casing

secured to the elevator shaft structure and into which said bolt extends, a latch in said casing adapted to engage said bolt, 60 and a weighted lever arranged entirely externally of the lock, engaging said latch and serving to move the latch into engagement with the bolt.

2. The combination with an elevator shaft 65 door, of a bolt on said door; a lock casing secured to the elevator shaft structure and into which the bolt extends, a latch in said casing adapted to engage said bolt, a weighted lever arranged entirely externally of the 70 lock, engaging said latch and holding it in engagement with the bolt, means for moving the lever to disengage the latch, and means for holding the latch in disengaged position. 75

3. In combination, an elevator shaft door, a lock for the door, a lever arranged entirely externally of the lock and associated with one of the moving parts thereof for normally holding it in closed position, means 80 adapted to be carried by the elevator car movable into engagement with the lever for opening the lock, and means operative upon the opening of the door for latching the lock in open position. 85

4. In combination, an elevator shaft door, a lock for the door, a bolt on the door arranged to engage the lock, a weighted lever arranged entirely externally of the lock and adapted to hold the lock normally in engagement with the bolt, a projection on the lever, a slotted actuating member adapted to be carried on an elevator car for engaging said projection, means for moving said member to disengage the lock from the bolt, and means operative by the removal of the bolt from the lock for holding the lock in disengaged position.

5. In combination, an elevator shaft door, a motor driven car, a motor controller on 100 the car, a bolt for the door, a latch on the elevator shaft for engaging the bolt, a lever arranged entirely externally of the lock for normally holding the latch in closed position, a projection on said lever, a slotted 105 actuating member on the car adapted to engage said projection, mechanism carried by the car for moving said member to open the lock, and means operative simultaneously with said mechanism for locking the 110 motor controller in neutral position.

In testimony whereof, I have hereunto set my hand.

WILLIAM H. HARTMAN.
